FOREIGN PATENT DOCUMENTS

EM 01248447-0001 1/2011

* cited by examiner

Primary Examiner — Jennifer Rivard(74) Attorney, Agent, or Firm — David K Mattheis; Kim W Zerby(57) CLAIM

We claim the ornamental design for the cleaning center for a shaver, as shown and described.

DESCRIPTION

FIG. 1 is a perspective view of a cleaning center for a shaver;

FIG. 2 is a front view thereof;

FIG. 3 is a right side view thereof;

FIG. 4 is a rear view thereof;

FIG. 5 is a left side view thereof;

FIG. 6 is a top plan view thereof; and,

FIG. 7 is a bottom view thereof.

The broken lines shown in the drawings illustrate portions of the article and form no part of the claimed design.
